(57) **CLAIM**

The ornamental design for a combined back scrubber and applicator band, as shown and described.

DESCRIPTION

FIG. 1 is an isometric view of a combined back scrubber and applicator band showing my new design;

FIG. 2 is a front elevation view thereof;

FIG. 3 is a rear elevation view thereof;

FIG. 4 is a right side elevation view thereof, the opposite side being a mirror image of the shown;

FIG. 5 is a top plan view thereof, the bottom being a mirror image of the shown; and,

FIG. 6 is a rear elevation view of an alternate embodiment thereof, the only differences residing in the reversal of the curvilinear contour along the sides and the appearance of the rear layer.
